NEGATIVE GLOWLAMP

Harvey C. Rentschler, East Orange, and Donald E. Henry, Bloomfield, N. J., assignors to Westinghouse Lamp Company, a corporation of Pennsylvania

Application March 20, 1929, Serial No. 348,409

7 Claims. (Cl. 176—122)

This invention relates to gaseous conduction devices in which rarefied gases are rendered luminous by the sustained passage of electric current between electrodes, and more particularly to lamps of this type in which the luminosity is due to a negative glow discharge.

One of the objects of the invention is to produce a negative glow lamp which may be operated from an ordinary 110 volt alternating current 10 lighting circuit, with or without the inter-positioning of a ballast resistance or other current limiting device in series therewith.

Another object is to produce a glow discharge device which will have a stable operating characteristic.

Another object is to produce a glow discharge television lamp of uniform glow and high intrinsic brilliancy.

A still further object is to produce an electrical discharge device, employing a rare gas in which gas purifying conditions are provided continuously during the operation of the device.

Other objects and advantages will hereinafter appear.

It has been necessary, in the operation, on commercial line voltages, of negative glow lamps or similar gaseous discharge devices, as heretofore constructed, to employ a current limiting means in series therewith in order to prevent arcing

30 between the electrodes and the establishment of an unstable electrical discharge. Usually such current limiting device consists of a high resistance located in the base of the lamp and connected in series with one of the electrodes.

35 In the absence of such current limiting means, the glow discharge cannot be maintained, but immediately forms a destructive arc which causes destruction of the device.

We have discovered, however, that if one of the 40 rare gases such as neon, is employed at a suitable pressure, as the gaseous filling within the device and the electrodes are properly spaced apart and are composed of thorium, the lamp may be operated with a stable electrical discharge without the use of current limiting means in series 45 therewith, on an ordinary 110 volt alternating current line. The thorium electrodes have a low cathode fall and the voltage required to start the discharge is near the peak voltage of the alternating current source. Since the vapor pressure of the thorium is so low that it does not assist in carrying current through the device, the arcing voltage of the lamp is relatively high, that is, above the peak voltage of the 110 volt 50 alternating current line and consequently when

the lamp is operated directly from the 110 volt line, the discharge cannot break down into an arc.

It has been proposed heretofore to employ an alkali metal on the electrodes to reduce the cathode drop but when so employed, the arcing potential is reduced below the peak voltage of the 5 110 volt alternating current source and such devices require the use of a current limiting resistance in series therewith to render the discharge 10 stable.

Negative glow discharge lamps of this type are useful for many purposes where only a small amount of light is desired at a low current consumption, such as indicator and signal lamps and 15 in household applications. The current consumption of a small neon lamp, such as used on electric light switches is so low that they may be operated continuously to indicate the location of the switch at night. They are also useful for indicating when current is turned on in 20 electrical appliances, such as electric irons, etc.

It is highly desirable that such lamps operate without the necessity of a current limiting resistance in series therewith, in order to economize 25 in space. The elimination of the ballast resistance also effects a considerable saving in the cost of the lamp.

In addition to rendering the discharge stable, the use of thorium electrodes, enables a more 30 uniform operating characteristic to be obtained for the lamps and permits the use of a high current density on the electrode without objectionable sputtering.

One important application of the negative glow 35 lamp is in a light source for television apparatus. In such lamps the electrodes are composed of two parallel flat sheets of metal, placed close together so that the discharge occurs only on the outside of the electrode serving as the cathode. The plates are of the same size or slightly 40 larger than the picture to be reproduced and the cathode is observed through a scanning disc, as is well understood in television reception. Difficulty has been experienced in such lamps, as 45 heretofore constructed, due to the fact that the degree of illumination of the cathode is small. The materials ordinarily used for the cathode, are iron or nickel and when employing such metals, the current density of the electrode must 50 be maintained low to prevent sputtering of the electrodes. According to Claude Patent 1,125,476 the current density must be maintained below two thirds ampere per square decimeter area of 55 the cathode.

When employing such materials as nickel and iron as the cathode of television lamps, the glow on the cathode is often not uniform over the surface but has irregular spots which are either 5 brighter or darker than the average intensity of illumination of the cathode.

The bright portions are believed to be due to traces on the electrode of materials of lower cathode resistance than the material of the electrode, 10 such as one of the alkali metals and the dark portions to accumulations of materials of higher cathode resistance, such as carbon. It is extremely difficult to clean iron or nickel electrodes of such materials, so as to eliminate this spotty 15 condition.

We have found that when thorium is employed as the cathode that the current density at the electrode may be very much higher without objectionable sputtering or deterioration and as a consequence the brilliancy of the electrode is materially increased.

Thorium, moreover, does not exhibit the spotty appearance of the iron or nickel electrodes. Due to the chemical activity of thorium it is self-cleaning, so that foreign materials having a higher or lower cathode resistance than thorium 25 do not remain on the thorium cathode.

The sputtering of the electrodes in a gaseous conduction device of this nature we have found 30 to be due, to the voltage drop at the surface of the cathode, rather than to the current density at the electrode and the steeper the voltage-current characteristic curve of the device, the greater the tendency of the cathode to sputter. Comparative measurements made with thorium and 35 iron or nickel electrodes have shown that for a given increase in current density at the cathode, the increase in voltage drop at the electrode is substantially only one half as great with a cathode composed of thorium, as with a nickel or iron cathode, so that the voltage-current characteristic curve for the device when employing a thorium cathode is only half as steep as when the cathode is composed of iron or nickel and 40 similar materials.

We have also discovered that there is a definite relation between the steepness of the voltage-current curve and pressure of the gas employed 45 and that by arranging the electrodes so as to permit the utilization of a high gas pressure, the slope of the voltage-current curve of the device may be still further reduced so that a materially higher current density may be employed on the cathode without an increase in the voltage drop 50 at the electrode sufficient to cause deleterious sputtering of the cathode.

In television lamps as now constructed, the gas pressure which can be used is limited by the permissible spacing of the parallel plate electrodes. As the gas pressure is increased the plates must be brought closer together in order to maintain the spacing therebetween well within the mean free path and hence to prevent discharges occurring on the reverse side of the cathode. However, there is a mechanical limit to the closeness to which these electrodes may be spaced which limits the maximum gas pressure which 55 may be used.

In accordance with the present invention this 60 difficulty has been overcome and a high gas pressure employed by placing solid insulating material between the electrodes and in contact therewith so as to positively restrict the discharge to the face thereof. This insulating material 65 may consist of an interposed sheet of mica or

similar material of high dielectric strength or it may consist of an insulating coating on the back of the cathode. When high electrical efficiency is not of particular importance as compared with the importance of a high intrinsic brilliancy of the cathode, the anode may be of any convenient shape, as a wire spaced from the cathode a distance greater than the mean free path and the discharge allowed to go to both sides of the cathode.

The glow on the reverse side of the cathode is not utilized but such construction permits a relatively high gas pressure to be employed so that the current density and hence the brilliancy of the observed side of the cathode is 10 high.

The invention may be embodied in various forms and in order that a more complete understanding of the invention may be had reference is made to the accompanying drawings, in which 20

Fig. 1 is a side view of one form of lamp constructed in accordance with my invention and employing auxiliary starting tips.

Fig. 2 is a curve showing the relation between the operating voltage and current of the 25 lamp shown in Fig. 1.

Fig. 3 is a side view of a modified form of lamp which does not require auxiliary starting tips for low voltage starting.

Fig. 4 is a further modification employing 30 thorium for the starting tips only.

Fig. 5 is a perspective view of a television lamp.

Fig. 6 is a side elevation of a modified television lamp capable of operation in a high gas pressure.

Fig. 7 is a perspective view of a further modified television lamp in which the anode is spaced outside of the mean free path of the gas, and

Fig. 8 is a perspective view of a negative glow television lamp for producing a concentrated 40 glow of small area.

The lamp shown in Fig. 1 comprises an envelope 11 containing a pair of spaced apart electrodes 12 and 13 supported upon rigid stems 14 and 15 sealed in a press 16. The stems 14 and 15 45 are joined to leading-in conductors 17 and 18 connected to the terminals 19 and 20 of the lamp base 21.

The electrodes 12 and 13 are composed of thorium, which has a cathode drop of such value 50 that when the electrodes are spaced apart at the critical distance for the minimum starting potential, in neon gas at a substantial pressure, the discharge will start below the peak voltage of an ordinary commercial 110 volt A. C. line, but 55 sufficiently near to the peak voltage so that the normal arcing voltage of the lamp will be above the peak voltage.

The anodes 12 and 13 may be secured to the support wires 14 and 15 in any suitable manner, 60 such as by being threaded thereon, but in the embodiment shown, the support wires pass through an opening in the anode and the anode is compressed about the support to frictionally engage the same.

A gaseous filling of argon, neon, helium or mixtures thereof may be employed at a reduced pressure, but neon is preferred in order to bring the starting and arcing voltages respectively below and above the peak voltage of the 110 volt 70 A. C. line. The pressure of the gas may range from 5 mm. to 3 or 4 cm. When employing argon lower pressures are preferable and in the case of helium higher pressures may be used.

In order to obtain a minimum starting poten- 75

tial for the device a pair of starting tips 22 and 23 are secured to the support wires 14 and 15 respectively and terminate in proximity to the electrodes 13 and 12.

5 The space between the end of the starting tips and the electrodes should be such as to enable the minimum potential to be obtained for starting the discharge. This distance is dependent upon the particular gas employed and the pressure thereof. For instance, with a filling of neon gas at a pressure of from 5 to 8 mm. of mercury, a spacing of approximately 1 mm. has been found to give the requisite low potential starting conditions.

10 15 If other pressures are used or other gases employed it may be necessary to slightly vary the spacing of the starting tip from the cathode to obtain the minimum starting potential conditions. The discharge, having started between one of the electrodes and the adjacent starting tip, immediately spreads to the other electrode.

15 The discharge lamp just described, employing neon gas, may be placed in the ordinary incandescent lamp socket and operated directly on a 110 volt A. C. commercial lighting circuit without employing a stabilizing resistance and will operate under such conditions with a stable electrical discharge. This is contrary to the behavior of negative glow discharge lamps of the same general character, as heretofore constructed. The reason for this behavior of the lamp will be better understood by reference to the characteristic curves shown in Fig. 2.

20 25 In Fig. 2, curve A represents the voltage-current relation of the discharge through a negative glow lamp of the prior art type, employing iron or nickel electrodes. Such a lamp requires a relatively high voltage D, to break down the cathode resistance and initiate a discharge therethrough. After the discharge has been started, however, the lamp may be operated at a relatively lower voltage E provided a current limiting resistance is used.

25 30 As the operating voltage is increased, the current through the lamp increases quite rapidly until the cathode becomes entirely covered with a luminous glow. This portion of the curve is represented by the line EF. After the cathode becomes entirely covered with the cathode glow a further increase in voltage increases the current density of the discharge at the surface of the cathode until, when the voltage is raised sufficiently, the glow discharge suddenly breaks down into an unstable arc discharge.

35 40 45 This point is indicated at G in the curve. When this condition is reached the current through the lamp increases enormously and results in sudden destruction of the lamp. Such a lamp cannot be started on an 110 A. C. line since the starting voltage D is above the peak voltage of such a line and if operated on a 220 volt A. C. line, the discharge passes immediately to a destructive arc, in the absence of a current limiting means, since the arcing voltage G is below the peak of the 220 volt A. C. line.

50 55 60 65 70 75 Curve B represents the voltage and current relation of the discharge when employing thorium electrodes in neon at the same pressure as that employed in the lamp from which the curve A was obtained. With this lamp the discharge starts at H, below the peak voltage of the 110 volt line and the arcing voltage is above the peak voltage so that when such a lamp is operated on an ordinary 110 volt A. C. line, the maximum available voltage is not sufficient to start the arc

75 discharge and the discharge cannot pass from the stable glow discharge to the runaway arc discharge.

If it is desired to operate the lamp on a 220 volt line with a stable discharge, helium may be substituted for the neon, since with helium gas the starting and arcing voltage fall respectively below and above the peak of the 220 volt A. C. line.

80 85 90 95 In Fig. 3, we have shown a construction in which the starting tips have been eliminated and the electrodes 24 and 25 brought close together at one end to provide the minimum spacing necessary for low voltage starting. In this lamp the support wires 26 and 27 for the electrodes are enclosed within insulating sleeves 28 in order to restrict the discharge to the electrodes. This is desirable in many instances since the materials, such as nickel, of which the electrode supports are constructed, tend to sputter at the operating voltage and cause a gradual blackening of the envelope.

100 105 110 115 120 125 130 135 140 145 150 155 160 165 170 175 180 185 190 195 200 While the electrodes illustrated in Fig. 3 are composed of a rod of thorium, it is to be understood that they may take other forms such as parallel plates, or intertwined spirals. In Fig. 4 we have shown a lamp having a pair of spaced plate electrodes 29 and 30 which may be composed of nickel, or iron or similar material between which the discharge takes place. In order to initiate the discharge at a low potential, a pair of starting tips 31 and 32 composed of thorium, are employed. The discharge from such a lamp has somewhat the same characteristic as one, the electrodes of which, are composed entirely of thorium. That is, due to the thorium starting tips, the discharge in neon will start below the peak of the 110 volt A. C. line and the arcing voltage will be well above the peak voltage, so that a stable discharge is obtained without any current limiting device. However, due to the greater tendency of iron or nickel to sputter, it may be desirable, in some instances to limit the current somewhat by a resistance in series with the electrodes.

205 210 215 220 225 230 235 240 245 250 255 260 265 270 275 280 285 290 295 300 The thorium electrodes in addition to their property of having a low cathode drop also exert a clean-up action or gas purifying action and maintain the gas in a pure condition, thus enabling the operating characteristics to be maintained over a long commercial life. In addition to these advantages the thorium electrodes are more resistant to sputtering at high current densities.

305 310 315 320 325 330 335 340 345 350 355 360 365 370 375 380 385 390 395 400 We have found that the resistance to sputtering of an electrode, in a glow discharge device, depends, not on the current density at the electrode, as ordinarily presumed, but on the voltage drop at the cathode.

405 410 415 420 425 430 435 440 445 450 455 460 465 470 475 480 485 490 495 500 This voltage drop or resistance to the discharge at the cathode, increases as the current density increases but when thorium is employed as the cathode, we have discovered that the increase in voltage drop is only about one-half of that obtained when iron, nickel or similar materials are used. For this reason it is possible to increase the current density to a much higher value with a thorium cathode than with ordinary metals. This is indicated from the characteristic curves of Fig. 2. The slope of the curve employing an iron cathode is much steeper than that for the thorium cathode at the same gas and pressure so that for given increase in the current through the lamp the increase in voltage is less for the thorium cathode than for the iron cath-

ode. The flatness of the voltage current curve is therefore an indication of the tendency of the cathode of such tube to sputter.

The sputtering may be further reduced by increasing the gas pressure since we have found that at higher gas pressures the voltage current characteristic curve is flatter. Curve C of Fig. 2 is the characteristic curve for a lamp constructed exactly the same as that from which curve B was made, but employing a higher pressure of neon. Such a lamp may be operated at extremely high current density on the cathode without objectionable sputtering. If it is assumed that the maximum voltage drop permissible without objectionable sputtering in the lamp of curve B, is of a value Y shown in Fig. 2, so that the maximum current which may be safely passed through the lamp is limited to a value X, it will be evident that at the higher gas pressure indicated by curve C that a very much higher current Z may be employed for the same voltage drop.

This possible increase in current density, while not important in certain types of lamps such as indicator lamps, is of extreme importance where high illuminosity is desired, as for television purposes, and in Figs. 5 to 8 inclusive are shown television lamps which are designed to be operated with a high current density on the electrodes.

The lamp shown in Fig. 5 has a pair of parallel closely spaced plates 33 and 34, one of which at least is composed of thorium. The thorium electrode is operated as the cathode, such a lamp being operated on direct current. The electrodes 33 and 34 are of a size at least as great as the area covered by the scanning disc of a television receiving apparatus and are spaced apart a distance which is within the mean free path of the gaseous filling so that the discharge takes place only between the outer surfaces of the electrodes. The electrodes are supported above a press 35 by suitable support wires 36 which also serve as current conductors. Such a lamp may be operated at a relatively high current density and therefore with a brilliant glow because of the resistance of the thorium cathode against sputtering. However, since the minimum distance which must be maintained between the plates 33 and 34 is limited by mechanical difficulties, it is not possible to increase the gas pressure above a definite limit without causing a discharge to take place between the inner faces of the electrodes.

In Fig. 6 we have shown a construction in which the gas pressure may be increased indefinitely while restricting the discharge to the outer face of the cathode, it being understood of course that the pressure must be maintained below that value at which arcing is likely to occur. In this figure the electrodes 33 and 34 are spaced apart by a sheet of solid insulating material 37 which may consist of mica or other suitable material.

If desired, in place of using the insulating spacer 37, the inner surfaces of the electrodes may be coated with insulating material or treated to render their surface insulating as by oxidation and the plates placed either in contact or at any convenient distance apart.

By increasing the gas pressure in such a lamp the characteristic curve may be made similar to that shown in curve C in Fig. 2 and the current density and hence the intrinsic brilliancy of the cathode increases very materially. The main purpose for restricting the discharge to the outside of the electrodes is for electrical efficiency since the glow on the inner surface of the cath-

ode can not be utilized. If electrical efficiency is not of importance the parallel plate anode may be replaced by an electrode of any other suitable shape and the discharge permitted to take place between the anode and both sides of the cathode. Such lamp is shown in Fig. 7 and comprises a thorium cathode 38 and an anode 39 of nickel or any other suitable material.

Since there is no appreciable sputtering at the anode of such a lamp this electrode may be made of small size and of any desired material. With a construction in Fig. 7 any suitable high gas pressure may be employed in order to increase the brilliancy of the discharge.

In Fig. 8 we have shown a lamp of the negative glow type adapted to produce a very intensive beam of light of small cross section. The lamp comprises two concentric cylindrical plates 40 and 41, the central cylinder 41 serving as a cathode and being composed of thorium and the outer cylinder 40 being spaced therefrom a distance which is within the mean free path of the gas employed.

In such a lamp all of the glow is confined to the interior surface of the cathode 41 and when such an electrode is viewed along the axis of the cylinder a very intense light source is produced which is useful in certain types of television photo-film apparatus and similar apparatus.

While a number of applications of our invention have been illustrated it is to be understood of course that many changes may be made in the construction of the device and that the invention may be embodied in other forms of gaseous conduction devices, such as rectifiers, and we do not desire to be limited to the exact details shown and described except in accordance with the appended claims.

What is claimed is:

1. A glow discharge lamp operable on an approximately 110 to 220 volt alternating current lighting circuit with a stable discharge without a current limiting means therewith, comprising an envelope containing a monatomic gas selected according to its starting and arcing voltage with respect to the peak voltage of the circuit in which it is designed to operate, a pair of electrodes therein, at least one of said electrodes being composed of thorium, the discharge initiating and operating potentials of said lamp being no greater than the peak voltage of the alternating current lighting circuit and the arcing potential of said lamp being greater than the peak voltage of said A. C. lighting circuit.

2. A glow discharge lamp operable with a stable discharge on an approximately 110 to 220 volt alternating current line, comprising an envelope, a pair of electrodes therein, a filling of rare gas selected according to its starting and arcing voltage with respect to the peak voltage of the circuit in which it is designed to operate, at least one of said electrodes being composed of thorium metal, a portion of one electrode closely approaching the other electrode, the minimum spacing of electrodes being such that the voltage required to initiate a discharge through said lamp is materially lower than the arcing potential of said device.

3. A glow discharge lamp of the negative glow type operable with a stable electrical discharge directly on an approximately 110 volt alternating current lighting circuit, comprising an envelope, an atmosphere of neon therein at a reduced pressure, a plurality of electrodes therein, at least one of which is composed of thorium,

one of said electrodes being disposed, in part, in proximity to another electrode, the minimum spacing of the electrodes being such that the voltage required to initiate a discharge through the lamp is materially lower than the arcing voltage of said lamp.

4. A glow discharge lamp of the negative glow type operable with a stable electrical discharge directly on an approximately 110 volt alternating current lighting circuit comprising an envelope, an atmosphere of neon therein, at a reduced pressure, a plurality of electrodes therein, at least one of which is composed, at least in part, of thorium metal, one of said electrodes being disposed from said other electrode at a distance of about one millimeter, the discharge initiating and operating potentials of said device being no greater than the peak voltage of said lighting circuit but the arcing potential of said device being greater than the peak voltage of said lighting circuit.

5. A glow discharge lamp of the negative glow type operable with a stable electrical discharge directly on an approximately 110 volt alternating current lighting circuit comprising an envelope, an atmosphere of neon therein at a pressure of from three to thirty millimeters of mercury, a plurality of electrodes therein, at least one of which is composed, in part, of thorium, one of said electrodes being disposed from another electrode at a distance of about one millimeter, the discharge initiating and operating potentials of said lamp being no greater than the peak voltage of said circuit but the arcing voltage of said device being greater than the peak voltage of said lighting circuit.

6. A gaseous conduction lamp comprising an envelope, containing a rare gas at a substantial pressure, said gas being selected in accordance with its starting and arcing voltage with respect to the peak voltage of the circuit in which it is designed to operate, a cathode and an anode within said envelope, said cathode consisting of thorium, the discharge initiating and operating potential of said device being no greater than the potential of an approximately 110 to 220 volt alternating current lighting circuit but the arcing potential of said device being greater than the peak potential of said circuit.

7. A gaseous conduction lamp comprising an envelope, containing a rare gas at a reduced pressure, said gas being selected in accordance with its starting and arcing voltage with respect to the peak voltage of the circuit in which it is designed to operate, a cathode and an anode therein, supporting conductors for said anode and cathode, a shield extending along substantially the entire length of said conductors for restricting discharge to the electrodes, said anode and cathode being cylindrical, said cathode being composed of thorium, said anode and cathode being close together at one end to facilitate starting and being much farther apart at the other end, the discharge and initiating potentials of said lamp being no greater than the peak voltage of an approximately 110 to 220 volt alternating current lighting circuit but the arcing potential of said device being greater than the peak potential of said circuit.
